Primary Examiner — Melanie Pellegrini

(57) **CLAIM**

The ornamental design for a buckle, as shown and described.

DESCRIPTION

1. Buckle
- 1.1: perspective
- 1.2: front
- 1.3: rear
- 1.4: right side
- 1.5: left side
- 1.6: top
- 1.7: bottom

The broken lines shown in the drawings illustrate portions of the buckle that form no part of the claimed design.
